To all whom it may concern:

Be it known that I, Theodore A. Schaad, a citizen of the United States, residing at Detroit, in the county of Wayne and State of Michigan, have invented a new, original, and ornamental Design for an Airplane Toy, of which the following is a specification, reference being had to the accompanying drawing, forming a part thereof, in which:

Fig. 1 is a side elevational view of an airplane toy embodying the invention; and

Fig. 2 is a top plan view.

I claim:

The ornamental design for an airplane toy, substantially as shown.

THEODORE A. SCHAAD.
